DESIGN FOR A DOUBLE DOOR STOP

Rufus A. Mann and William H. Mills, Kingsport,
Tenn.

Application June 22, 1940, Serial No. 93,181

Term of patent 7 years

To all whom it may concern:

Be it known that we, Rufus A. Mann and William H. Mills, citizens of the United States, residing at Kingsport, in the county of Sullivan and State of Tennessee, have invented a new, original, and ornamental Design for a Double Door Stop, of which the following is a specification, reference being had to the accompanying drawing, forming part thereof.

Figure 1 is a top plan view of a double door stop showing my new design.

Figure 2 is an end elevational view.
Figure 3 is a side elevational view.

Figure 4 is a vertical longitudinal sectional view taken through Figure 1 approximately on the line 4—4 and looking upwardly in the direction of the arrows.

We claim:

The ornamental design for a double door stop, as shown.
